CLAIM

The ornamental design for an electrical housing as shown and described.

DESCRIPTION

FIG. 1 is a front-top-right perspective view of an electrical housing showing our new design;

FIG. 2 is a rear-top-right perspective view of the electrical housing shown in FIG. 1.

FIG. 3 is a front view of the electrical housing shown in FIG. 1.

FIG. 4 is a top view of the electrical housing shown in FIG. 1.

FIG. 5 is a rear view of the electrical housing shown in FIG. 1.

FIG. 6 is a bottom view of the electrical housing shown in FIG. 1.

FIG. 7 is a right side view of the electrical housing shown in FIG. 1; and,

FIG. 8 is a left side view of the electrical housing shown in FIG. 1.

The broken lines in the drawings show portions of the electrical housing that form no part of the claimed design.

1 Claim, 8 Drawing Sheets
